[57] CLAIM

The ornamental design for a optical image bar for an electrophotographic printer, as shown and described.

DESCRIPTION

FIG. 1 is an enlarged partial perspective view of an optical image bar for an electrophotographic printer showing my new design and shown broken away for ease of illustration;

FIG. 2 is a reduced front elevational view thereof;

FIG. 3 is a top plan view thereof;

FIG. 4 is a left side elevational view thereof;

FIG. 5 is a right side elevational view thereof;

FIG. 6 is a rear elevational view thereof; and,

FIG. 7 is a bottom plan view thereof.

FIG. 1

FIG. 6

FIG. 3

FIG. 2

FIG. 7

FIG. 4

FIG. 5
